CLAIM

The ornamental design for a deployable step, as shown and described.

DESCRIPTION

FIG. 1 is a front perspective view of a deployable step depicting our new design;

FIG. 2 is a top view thereof;

FIG. 3 is a front plan view thereof;

FIG. 4 is a side view thereof;

FIG. 5 is an opposite side view thereof;

FIG. 6 is a bottom view thereof;

FIG. 7 is a rear plan view thereof; and,

FIG. 8 is a rear perspective view thereof.

The broken lines depict portions of the deployable step which form no part of the claimed design.
